VARIABLE TUNING MECHANISM

Frank W. Godsey, Jr., North Adams, Mass., assignor to Sprague Specialties Co., North Adams, Mass., a corporation of Massachusetts

Application June 24, 1940, Serial No. 342,156

4 Claims. (CL. 74—10)

The present invention relates to an improved method and means for actuating the tuning elements of a radio receiver and more particularly to novel driving means for actuating a condenser gang comprising tuning condensers of the type described in the copending application of Robert C. Sprague and Frank W. Godsey, Jr., Serial No. 336,822 filed May 23, 1940, now U. S. Patent No. 2,324,178 issued July 13, 1943.

The tuning condenser described in said application comprises condenser units the electrodes of which consists of two closely-spaced concentric conducting cylinders which are displaceable relative to each other, to vary the capacity of the condenser. Interposed between the electrodes is a dielectric layer which preferably consists of a vitreous material forming a fused integral coating on the surface of the inner electrode. Preferably the electrodes and the coating are made in their coacting dimensions to close tolerances as to engage each other with a smoothly sliding fit.

Tuning condensers of this type have many advantages, as they combine a wide capacity range, great mechanical and electrical stability throughout their capacity range with a small size, compact and light weight structure, and can be manufactured at low cost.

Such tuning condensers possess inherently a linear capacity-stroke characteristic, but by means of suitable mechanical driving means the relation between the capacity of the condenser and the displacement (or rotation) of the tuning control can be made of any other desired character.

By observing the various requirements specified in the above referred to copending application of R. C. Sprague et al., condenser of this type can be made to capacity tolerances of plus/minus 1% and even less. In practice however, such condensers are more feasibly made to tolerances of about plus/minus 5% and consequently the individual condensers of an assembly may correspondingly differ both in their capacity range and in their minimum and maximum capacity values.

Such wider capacity tolerances as a rule, do not fully meet practical requirements. Furthermore, in certain applications, for example, in super-heterodyne radio receivers, the tuning condenser of the oscillator circuit must possess a different capacity range from that of the remaining tuning condensers; to achieve this in the past either so-called "cut-plate" tuning condensers have been used or an extra "padder" condenser was inserted in series with the tuning condenser of the oscillator circuit.

It is an object of this invention to provide novel actuating and driving means for tuning condensers comprising as their main elements two concentric cylindrical electrodes.

5 Another object of the invention is to provide novel actuating and driving means for a tuning condenser gang comprising condensers of the above described type, and by which driving means the individual condensers can be made to exhibit identical capacity ranges and capacity values, or different capacity ranges and different minimum and maximum capacity values, so as to meet the particular requirements of their respective circuits.

10 A further object of the invention is to provide a novel driving means for the condensers of a tuning condenser assembly by which various relationships can be achieved between the capacity ranges and values of individual condensers of a gang and the displacement (or rotation) of the tuning control means of the gang.

15 These and further objects of the invention will appear as the specification progresses.

The invention will be described with reference 20 to the appended drawings forming part of the specification and in which:

Figure 1 is a side view, partly in section, of a tuning condenser gang using one embodiment of the actuating and driving means of the invention, which enables the tuning condensers—the individual condenser units of which are made to capacity tolerances which can be easily achieved in mass production—to meet the particular requirements and accurate tuning of its tuning 25 circuits.

Fig. 2 is a plan view of the condenser gang of Fig. 1.

Fig. 3 is a diagrammatic illustration of a 30 method by which the actuating and driving means of the invention permits each condenser of the assembly to assume an individual relationship between its capacity setting and the displacement (or rotation) of the common tuning control means.

45 Fig. 4 is a side view illustrating another embodiment of the driving means of the invention as applied to a tuning condenser of a construction similar to that of Figs. 1 and 2.

Fig. 5 is a side view illustrating a modification 50 of the driving means shown in Fig. 4.

Referring to Figs. 1 and 2, the tuning condenser gang there shown comprises two condenser units supported on a common metal mounting base 55 which in practice is preferably the chassis of the radio receiver in which the condenser gang

is used. The two condensers are identical in construction and each comprises an electrode 10 consisting of a hollow metal cylinder or sleeve preferably closed at one end, and an electrode 11 consisting of a hollow metal sleeve surrounding the electrode 10. Interposed between the electrodes 10 and 11 is a concentric dielectric layer 12 forming an integral coating on the surface of electrode 10. The dielectric layer 12 consists preferably of a potassium-lead silicate vitreous enamel as disclosed in the copending application of Stanley O. Dorst, Serial No. 289,292, filed August 9, 1939, now U. S. Patent No. 2,290,947 issued July 28, 1942. The layer 12 may also consist of other suitable dielectric materials, for example, of various kinds of vitreous enamels, or may consist of a non-vitreous dielectric material such as cellulose acetate, polystyrene, hard rubber or the like, to which dielectric materials may be added a filler of titanium dioxide or other dielectric material to increase the dielectric constant and/or lower the power factor.

The layer 12 is applied to the electrode 10 preferably by the cataphoretic deposition process described in the copending application of Preston Robinson et al., Serial No. 197,692 filed March 23, 1938, which process produces a coating of high uniformity and of even thickness throughout the length of the coating. As a rule the so deposited coating is fused and thereafter subjected to surface grinding as described in the above referred to copending application of Robert C. Sprague et al., whereby the coated electrode 10-12 engages the sleeve electrode 11 with a sliding fit whereby the air layer or gap 13 formed between the elements is preferably .00025" to .0005" thick.

For the guiding of the coated electrode 10-12 in its movement relative to the sleeve electrode 11, there is provided a guide cylinder 22 abutting against the closed end of the electrode 10-12 and consisting of a low-loss insulating material such as "Bakelite," hard rubber, "Isolantite," or the like. Guide 22 is preferably hollow throughout its length except for the portion 23 abutting the electrode 10-12. At their adjacent ends the electrode 10-12 and the guide 22 are provided with axial bores through which passes a spindle bolt 21 secured by a nut 37.

Each condenser is supported on the base 15 by a metal mounting bracket 14 secured to the sleeve electrode 11 through a mounting strip 16 which is soldered or otherwise secured to the outer surface of the sleeve 11, and an insulating strip 17 of hard rubber, "Bakelite," "Isolantite" or the like interposed between the strip 16 and the bracket 14. These members are secured together respectively by a countersunk screw 18 passing through the strip 17 and engaging a suitable tapped hole of the strip 16 and by a countersunk rivet 19 passing through the strip 17 and the bracket 14.

The bracket 14 is secured to the base 15 by a screw 20 passing through the base 15 and threadedly engaging a suitable tapped hole of the bracket 14.

The electrode 11 is provided for its external electrical connection with a terminal lug 24 consisting of an extending portion of the strip 16 whereas the coated electrode 10-12 is maintained at ground potential by the spindle bolt 21 which passes through and contacts an upright extending portion 38 of the bracket 14. The portion 38 also serves as a guide for the spindle 21 and as a stop to limit the lateral movement

of the coated electrode 10-12 at the maximum capacity position.

The actuating and driving means for tuning the condensers of the assembly comprises for each condenser the spindle bolt 21 above referred to, two couplers 25 and 30, a connecting rod 26, and a crank 27 and a hub 28 mounted on a driving shaft 29 which shaft is common to all of the condenser units.

10 The coupler 25 consists of a metal block having a threaded central bore 31 extending throughout the greater portion of the length of the coupler and adapted to receive the spindle 21.

15 The coupler 30 is a metal block, internally threaded throughout its length and is mechanically connected to the coupler 25 by means of the rod 26 and pins 32 and 33 passing through the ends of the rod and affixed to the couplers 25 and 30 respectively.

20 The crank 27 consists of a metal spindle bolt one end of which is secured within a radial bore of the hub 28 in such a manner as to permit the free rotation of the spindle while preventing its radial movement relative to the hub. This is 25 accomplished by a lock screw 35 which passes through the hub 28 and engages an annular notch 34 of the spindle 27. The extending portion of the spindle 27 is threaded throughout its length and engages the corresponding threads 30 of the coupler 30.

A set screw 36 secures the hub 28 to the shaft 29. A tuning control (not shown) is affixed to one end of the shaft 29 in well known manner.

25 The couplers 25 and 30 and the crank 27 form the two adjustment means of the actuating and driving means of the invention, by means of which each condenser of the tuning condenser gang can assume the tuning range and minimum and maximum capacity values, which meet the 30 particular requirements of its tuned circuit.

Thus in the embodiment of the invention shown in Figs. 1 and 2 the capacity range of each condenser unit, limited by the horizontal and vertical positions of the crank 27, is determined by the extent of travel of the coated electrode 10-12 through the sleeve 11 and this can be adjusted by varying the effective length of the crank 27 by its threading or unthreading through the coupler 30.

35 The upper or lower capacity values of each condenser is adjusted by its spindle 21 threading a greater or a lesser length of the corresponding coupler 25, thus setting the initial position which the coated electrode 10-12 assumes with respect to the sleeve electrode 11. Whether the spindles 21 of the individual condensers should engage their corresponding couplers 25 to the same or different extents, and thus whether the coated 40 electrodes 10-12 of the individual condensers are correspondingly displaced relative to each other, is determined by the differences in the characteristics of the individual condensers and by the particular requirements of their associated circuits. In general because of the above 45 factors, the degree of engagement is different for each condenser unit and this has been shown in Fig. 2 in which the electrode 10-12 of the lower condenser is shown to be displaced a distance D relative to the corresponding electrode of the upper condenser.

50 The actuating and driving mechanism of the invention not only permits the individual adjustment of the capacity range and the minimum and maximum capacity values of each condenser 55 unit of a gang, but also makes it possible to pro-

75

vide a different rate of change of capacity with displacement (or rotation) of the common tuning control means. This is achieved by displacing the individual cranks 27 of the condensers a predetermined angle relative to each other. This is shown in Fig. 3 where the crank 27 of the upper condenser is shown to lead the crank 27 of the lower condenser by an angle β . In Fig. 3 the shaft 29 is shown to be rotated through an angle α from its end or minimum capacity position. By so displacing the crank 27 the upper condenser unit exhibits throughout its capacity range a greater rate of change of capacity than does the lower condenser unit.

In such instances where the cranks 27 are displaced relative to each other as above described, one limit of the capacity range may occur when the crank of the lower condenser is in the horizontal position and the other limit may occur when the crank of the upper condenser is in the vertical position.

Thus, by adjusting the angle β between the two cranks 27, and by adjusting the upper and lower capacity limits and the stroke of each individual condenser element, the two condenser units may be made to "track" each other approximately as required, for instance, for the simultaneous tuning of the oscillator and antenna circuits of superheterodyne radio receivers.

In Fig. 4 there is shown a second embodiment of the actuating and driving means of the invention. While in Fig. 4 only one condenser unit is shown, it should be well understood, that the invention is applicable to a tuning condenser gang having a plurality of condenser units.

The actuating and driving means illustrated in Fig. 4 comprises for each condenser 41 a spindle bolt 50 similar to the spindle bolt 21 described in connection with the tuning assembly of Figs. 1 and 2, a coupler 51, and a cam 52 affixed to a rotatable shaft 53 common to all of the condenser units.

The coupler 51 consists of a metal block internally threaded throughout the greater part of its length and into which the spindle bolt 50 threadedly engages. At its other end which engages the cam 52, the coupler 51 is either provided with a roller type cam follower or has a smooth, rounded surface, as shown at 54.

The cam 52 is a suitable disc preferably metal and its specific details and shape are determined by the particular requirements of the circuit in which its associated condenser is used. The stroke of the cam, which is the difference between the rise of the cam at the start and at the end of its movement, determines the displacement or stroke of the cam follower coupler 51 and hence the capacity range of the condenser, whereas the shape of the cam within the limits of its stroke determines the rate of change of the capacity of the condenser. The capacity values of the condenser at the limits of its capacity range can be varied by threading or unthreading the spindle bolt 50 in the coupler 51 which adjusts the initial relative position of the electrodes of the condenser 41 as has been fully described in connection with the tuning assembly of Figs. 1 and 2.

Thus by the use of an individual cam 52 for each condenser of the tuning assembly, and by means of the individual couplers 51, the capacity range, the upper and lower limits of the capacity range and the rate of change of capacity of each condenser, are made to meet the particular re-

quirements of each tuning circuit and the condensers can be made to "track" as required for the simultaneous tuning of the oscillator and antenna circuits of superheterodyne receivers.

5 To maintain the cam follower coupler 51 in positive contact with the cam 52 there is provided about the spindle bolt 50 a compression spring 55 one end of which abuts against the coupler 51 and the other end of which abuts against the bracket 42.

10 While the use of the compression spring 55 as shown in Fig. 4, fully meets the requirements of maintaining a positive contact between the cam follower 51 and the cam 52, such use has the 15 undesirable feature that a spring which is capable of exerting sufficient pressure in the beginning of the stroke requires a high force for its compression at the end of the stroke. At the same time the pressure exerted by the coupler 51 against the surface of the cam 52 increases with the degree of compression of the spring 55, and in some cases the pressure at maximum compression is so great that the rotation of the cam 52 by the coupler may disturb the setting of the 20 driving means.

25 In Fig. 5 I have shown an improved arrangement in which the above drawbacks are obviated. The driving mechanism there shown comprises a spindle bolt 60 (shown in part), a cam follower-coupler 61, and a cam 62 affixed to a rotatable shaft 63, whereby positive contact between the coupler 61 and the cam 62 is secured by a tension spring 65. One end of the spring 65 is secured to the coupler 61, for example, by a pin 66. I have found that if the other end of the spring 65 is fixed directly to the face of the cam, the required good contact between the coupler 61 and the cam 62 can be maintained without the spring being distorted to the full extent of 30 the stroke of the cam. If the spring 65 is secured to a point on the face of the cam at or approximating the center of the cam surface, no important change in the length of the spring takes place throughout the entire stroke of the cam and a constant pressure is exerted by the coupler 61 on the cam 62 irrespective of the rise of the 35 cam.

40 This is shown in Fig. 5 in which the spring 65 is secured to the face of the cam 62 by a pin 67 at a point corresponding to about the center of the cam surface, namely at a point from which substantially equal radii are formed to all effective portions of the cam surface.

45 It should be noted that whereas in the foregoing description, the actuating and driving means of the invention has been illustrated in its use with tuning condensers in which the inner electrode is movable and the outer or sleeve electrode is secured to a mounting base, such driving means are equally applicable for tuning condensers in which the outer electrode is movable and the inner electrode is affixed to a mounting base.

50 While I have described my invention by means of specific examples and in specific embodiments, I do not wish to be limited thereto for obvious modifications will occur to those skilled in the art without departing from the spirit and scope of the invention.

55 What I claim is:

60 1. In a condenser assembly having a plurality of condenser units each having a movable element, means for actuating the element comprising a threaded member engaging the element, a 65 coupler member engaging the threaded mem-

ber and adapted to adjust the element to a predetermined initial position, and a crank member having an adjustable effective length engaging said coupler member and adapted to displace the element to a predetermined second position, and means to simultaneously actuate all the elements and displace the same from their said initial position to their said second position, said means comprising a rotatable shaft common to all of the movable elements and to which the crank members are affixed.

2. In a condenser assembly having a plurality of condenser units each having a movable element, means for actuating each element comprising a threaded member engaging the element, a coupler member engaging the threaded member and adapted to adjust the element to a predetermined initial position, and a crank member having an adjustable effective length engaging said coupler member and adapted to displace said element to a predetermined second position, and means to simultaneously actuate all of the elements and displace the same from their said initial position to their said second position, said means comprising a rotatable shaft member common to all of the movable elements and to which the crank members of each element are affixed, said crank members being angularly displaced relative to each other about said shaft.

3. In a condenser assembly having a plurality of condenser units each having a movable element, means for actuating each element comprising a threaded rod member engaging the element, a coupler member engaging the rod member and adapted to adjust the element to a predetermined initial position, a second coupler member secured to said first coupler member,

and a spindle crank member threadedly engaging said second coupler member and having an adjustable effective length determined by the degree of engagement of said second coupler member and the crank member, said crank member being adapted to adjust the element to a predetermined second position, and means to simultaneously actuate all of the elements and displace the same from their said initial position to their said second position, said means comprising a rotatable shaft member common to all of the movable elements and to which the crank members of each element are affixed.

4. In a condenser assembly having a plurality of condenser units each having a movable element, means for actuating each element comprising a threaded rod member engaging the element, a coupler member engaging the rod member and adapted to adjust the element to a predetermined initial position, a second coupler member secured to said first coupler member, and a spindle crank member threadedly engaging said second coupler member and having an adjustable effective length determined by the degree of engagement of said second coupler member and the crank member, said crank member being adapted to adjust the element to a predetermined second position, and means to simultaneously actuate all of the elements and displace the same from their said initial position to their said second position, said means comprising a rotatable shaft member common to all of the movable elements and to which the crank members of each element are affixed, said crank members being angularly displaced relative to each other about said shaft.

FRANK W. GODSEY, JR.
